UNITED STATES PATENT OFFICE.

ELIAS FRANTZ, OF ALLENtown, ASSIGNOR OF ONE-HALF TO LEWIS GUTTENTAG, OF COPLAY, PENNSYLVANIA.

CAR-COUPING.

SPECIFICATION forming part of Letters Patent No. 453,978, dated June 9, 1891.

Application filed February 26 1891. Serial No. 382,945. (No model.)

To all whom it may concern.

Be it known that I, ELIAS FRANTZ, of Allentown, in the county of Lehigh and State of Pennsylvania, have invented certain new and 5 useful Improvements in Car-Couplings, of which the following is a specification.

The present invention consists in improvements applicable to existing railway-cars having pin-and-link couplings, whereby the same 10 are rendered automatic in coupling, and may be uncoupled without necessitating a train-man passing between adjacent cars.

The present improvements are illustrated in the accompanying drawings, wherein—

15 Figure 1 shows in longitudinal vertical section two adjacent draw-heads, the coupling-pin of one being shown elevated and that of the other lowered; and Fig. 2 shows a plan view of one of the draw-heads.

20 In the drawings, A A are chambered draw-heads of two adjacent and approaching railway-cars.

B B are the coupling-pins thereof, and C is a coupling-link.

25 Each pin B is pivotally connected at its upper end to the front end of a bar D, the rear end of which is pivoted to a stationary vertical bracket E, fixed to the draw-head. When the bar D is raised, the pin B is out of con-

30 nection with the link C, and when lowered the pin enters the link and so couples the cars. The bar D is maintained in its elevated position by a toggle-joint, the upper member F of which is pivoted to the bar D, and the lower

35 member G of which is pivoted at a to the draw-head or a fixed part thereof. The two members F G of the toggle-joint are connected by a knuckle-joint b. By bending or breaking the joint between the two toggle

40 members F G, the bar D, and with it the coupling-pin B, will drop. This is automatically effected by the entrance of the coupling-link C into the draw-head, having its coupling-pin elevated. The lower toggle member G con-

45 stitutes in itself a lever, since it is provided with a downwardly-extending extension or tail H below its pivot. To this extension is pivoted and suspended by a knuckle-joint c a pawl I. This pawl I is free at all times to

swing forward on its pivot, but cannot swing 50 on its pivot backward beyond a vertical plane when the bar D is raised. When the coupling-link C enters the draw-head, it encounters the pawl I, which is then located within the chamber of the draw-head, thus forcing the 55 pawl I and the lower toggle member C to swing backward on the pivot a, and consequently breaking the joint between the two toggle members and allowing the coupling-pin to drop into the link. In order to uncouple it, it is only necessary to lift the bar D. This can conveniently be done by a bail 60 J, extending beneath the bar D, said bail being carried by a rotary shaft K, extending to the sides of the car and having operating- 65 handles L. If when the uncoupling is effected the pawl I comes in front of the end of the link, it will not interfere with the withdrawal of the link, since the pawl will swing forward out of the way.

70 I claim as my invention.

1. In a car-coupling, in combination with the draw-head, the bar D, pivoted thereto, and at its front end the coupling-pin, and toggle-joint F G, pivoted at opposite ends to the 75 said bar D and draw-head, substantially as described.

2. In a car-coupling, in combination, the draw-head, bar D, toggle-joint F G, pivoted at opposite ends to the said bar and draw-head, 80 and the swinging pawl I, connected to the said toggle-joint and adapted to be engaged by the coupling-link to trip the coupling-pin, substantially as described.

3. In a car-coupling, in combination with 85 the bar D, pivoted to the draw-head, having the coupling-pin pivoted thereto, and toggle-joint composed of the members F G H, the bail J, extending beneath the bar D, and having crank-shaft K L, substantially as de- 90 scribed.

4. A chambered draw-head, a coupling-pin, a bar pivoted at opposite ends to said draw-head and pin, and a toggle-joint consisting of two members connected together by a 95 knuckle-joint, the upper of said toggle members being pivoted to said bar, and the lower of said toggle members being pivoted to the

draw-head and having a portion extending below said pivot, in combination with a pawl connected by a knuckle-joint to said downwardly-extending portion of said lower toggle

5 member, said pawl hanging within the chamber of the draw-head when said bar is raised, substantially as set forth.

In witness whereof I have hereunto signed my name in the presence of two subscribing witnesses.

ELIAS FRANTZ.
